16 Claims. (Cl. 338—180)

This invention relates to an adjustable electrical resistor wherein the resistance elements in the form of an electrically conductive film and, more particularly, to potentiometers using electrically conductive films of relatively low resistance values.

It is known to form adjustable electrical resistors in which the electrically resistive element consists of a carbon or metal film deposited by sublimation, evaporation, or other known techniques upon the inside of a tubular substrate or base member. In such resistors the inside of the tubular substrate usually is glazed prior to metal deposition. Terminations of an electrically conductive material are provided on the tube ends and a portion of the outside of the tube at each end. These terminations provide the necessary electrical path from the resistive element to the end caps which are force fitted on the outer tube diameter.

The resistive element is adjusted to a desired resistance value by a method known as "spiralling." Spiralling is accomplished through the use of an electric probe or an abrasive wheel to form a helical cut in the resistive element on the inside of the tubular substrate such that the resistive path is in the form of a helix or spiral. The resistance between the ends of the tubular substrate may be varied by changing the pitch of the spiral.

In units of relatively low resistance, however, unspiralled resistance elements often are used. When such low resistance elements are used, the typical point contact wiper causes a non-linear and unstable wiper displacement vs. resistance characteristic because of "field effects." Field effects is the term used to describe that phenomenon wherein the electrical current flows from the contactor or wiper radially into the resistive film in all directions before traversing the film and converging upon the other electrical termination. This radial distribution of the several current paths tends to increase the resistance offered to current flow. The problem is so severe that in a typical resistance element, the field effects can produce a much higher contactor-to-termination resistance than that existing between the electrical terminations on the tube ends. As such, the unit is non-linear and virtually useless as a variable resistor. In spiralled units the current path generally is relatively narrow, i.e., in the order of .03 inch wide. With such narrow current paths, there is little opportunity for radial current flow. Hence the problem of field effects generally is not encountered in spiralled units.

The problem of field effects can be overcome by the use of a multiple contactor instead of a single contactor. Various types of multiple contactors have been employed in the prior art. One such type involved the use of a circular piece of wire intended to contact virtually all points of the inner circumference of a film coated tubular base member. This type contactor has not been entirely satisfactory. Due to the normal surface irregularities of the tubular base member, the pressure of the contactor on the film resistance element tends to vary as the contactor is moved. Also the number of points on the film surface actually contacted tends to vary as the contactor is moved. These result in rather large non-linearities in the wiper displacement-resistance characteristic.

Another multiple contactor used a plurality of leaf springs, each positioned to contact a different radial point on the resistance film. Unfortunately, leaf springs have been found to be direction-sensitive. This direction-

2

sensitivity is due to the pressure differentials arising as the multiple contactor is either pushed or pulled along the film. Pulling the leaf spring contactor along the film lightens its pressure against the film and greatly increases noise or contact resistance. If the contactor is pushed, the converse is true, i.e., contact pressure increases which greatly decreases contact resistance. To overcome this directional sensitivity, the contactor length must be greatly reduced to produce translational forces that are tangential (not normal) to the film surface. Unfortunately such shortening greatly increases contact pressure and hence film wear.

Also some difficulty has been encountered in designing a contactor that is capable of maintaining constant film contact pressure with variations in the smoothness of the surface on which the film is deposited.

It is, therefore, an object of this invention to obviate many of the disadvantages of the prior art adjustable resistors.

Another object of this invention is to facilitate the positioning of an electrical contactor on an electrically conductive film.

Still another object of this invention is to provide an improved contactor for film type adjustable resistors.

In a preferred embodiment of this invention the adjustable resistor consists of an electrically non-conductive tubular base member which has a thin film of an electrically conductive material deposited on its inside wall. Terminals are placed at either end of the tubular base member so as to contact at least a portion of the thin film. End caps having openings are placed over either end of the tubular base member. The openings in the end caps are such as to coaxially position within the base member a contactor support or slider threaded on a lead screw.

In accordance with this invention a contactor formed of a helical wire toroid is mounted in a groove in the contactor support. The contactor support is spool-like with the contactor groove inclined with respect to its axis. The depth of the groove and the diameter of the wire helix forming the toroid are selected such that the toroid outer diameter is slightly greater than the maximum inner diameter of the tubular base member. Contact pressure between the turns of the wire forming the toroid and the film resistance element is obtained by the "fall-over" of the coil turns of the toroid when inserted within the tubular base member.

The frictional force of this pressure overcomes the rotational force of the lead screw. Due to this frictional force, rotation of the lead screw advances the contactor longitudinally along the resistance element. This arrangement has many advantages only one of which is that it provides a multipoint contact which greatly reduces the "field effects."

Further advantages and features of this invention will become apparent upon consideration of the following description read in conjunction with the drawing wherein:

FIGURE 1 is an isometric view of an adjustable resistor formed in accordance with this invention;

FIGURE 2 is an axial elevational cross-sectional view of the adjustable resistor illustrated in FIG. 1;

FIGURE 3 is an end partial-section view of the adjustable resistor illustrated in FIG. 1 taken along the partial-section line 3—3 of FIG. 2; and

FIGURE 4 is a perspective view of the slider of this invention.

The adjustable resistor or potentiometer shown in FIGS. 1 through 4 comprises a tubular ceramic base member 10 which may be formed of an electrically non-conductive material such as a ceramic. The adjustable resistor also includes a lead screw 12 on which is threaded

a follower 14. The follower 14 and lead screw 12 comprise the adjusting mechanism of the resistor. The adjusting mechanism is mounted by suitable end and header assemblies 16 and 18. This entire unit, including the base member 10, the adjusting mechanism and the end and header assemblies 16 and 18, respectively, is encapsulated and sealed by an epoxy resin. A terminal board 22 is placed adjacent the outside of the base member 10 prior to encapsulation to provide for an external electrical connection to both ends and to the follower of the adjustable resistor through pins 30, 31 and 32 in the terminal board 10.

Having thus described the overall configuration of the adjustable resistor, the specific details of its construction in accordance with this invention will now be described with particular reference to FIGS. 2, 3 and 4.

The tubular base member 10 consists of an electrically non-conductive tube on the inside of which is deposited a thin film 26 of an electrically conductive material, i.e., a resistance film. The resistance film 26 may be any of the known films such as a carbon film or a nickel composition deposited by sublimation, evaporation, or other known methods upon the ends and inner diameter of the tubular base member 10. Typically the inner diameter of the tubular base member 10 is glazed prior to metal deposition. Terminations 24 of an electrically conductive material such as a metallic frit or a gold plating are provided on the ends over the film 26 and on a portion of the outer diameter of each end of the tubular base member 10. These terminations 24 provide the necessary electrical path from the ends of film 26 to end caps 28 and 29. The end caps are metallic and are force fitted over the ends of the base member 10 to provide such electrical path. An external electrical connection to the end caps 28 and 29 is made through the respective pins 30 and 32 of the terminal board 22 to terminals 34 which are soldered to the respective end caps 28 and 29.

The end caps 28 and 29 are generally in the shape of cups having central openings therein to receive and mount the adjusting mechanism of the adjustable resistor. The adjusting mechanism includes the header assembly 18, and the end assembly 16 which mount and centrally locate the lead screw 12 coaxially within the base member 10. The header assembly 18 is made up of a slotted adjustment head 36 and a drive bushing 38 which are assembled into an integral unit by the use of a disc-like molding 40. The adjustment head 36 and drive bushing 38 are of a suitable metallic material whereas the molding 40 may be of a suitable plastic such as Teflon. The molding 40 aids in sealing the interior of the resistor. Preferably it has a low coefficient of friction to permit its rotation within the end cap 29. Also it desirably should be somewhat flexible and non-conductive to provide electrical insulation between the adjustment head 36, and the drive bushing 38 and the end cap 29.

The header end of the resistor is sealed by the use of elastic washers 56 placed on either side of the molding 40 and an additional bushing 52 which abuts the end of the resistor. This additional bushing 52 reduces wear on the molding 40 and aids in centrally locating the bushing 38.

The lead screw 12, whose center portion is threaded, may be gold plated for improved conductivity and corrosion resistance, and is fixedly coupled at one end to the drive bushing 38. Rotation of the slotted adjustment head 36 thus causes rotation of the lead screw 12. The other end of the lead screw 12 is rotatably supported by the end assembly 16 which includes the drive bushing 42 coaxially and fixedly supported within an outer bushing 54. The outer bushing 54 is of an electrically non-conductive material. A terminal 35 is soldered to the fixed bushing 42. The fixed bushing 42 is of a suitable metallic material and may have its bearing surface gold plated for improved electrical conductivity to the lead screw 12 so as to conduct current to the terminal 35. The terminal 35 is electrically connected (by means not shown such as

a wire) to the center pin terminal 34a and hence to the center pin 31 on the terminal board 22.

The follower 14 is normally made of any suitable material such as brass and preferably is rhodium plated for improved electrical conductivity, wear resistance, and corrosion resistance. It is threaded to allow mating with the thread of the lead screw 12. The outer bushing 54 acts as a seal and also an electrical insulator between the fixed bushing 42 and the left hand end cap 28. This end cap is force fitted over the left end (in the drawing) of the base member 10 to provide the electrical connection to the pin 30 from the left end of the film 26.

In accordance with the invention, the follower 14 is spool-like with a contactor groove 46 about its circumference. The groove 46 lies in a plane that is inclined with respect to the axis of the spool-like or cylindrical shaped follower 14. The contactor comprises a coil having a plurality of turns of a fine wire formed into a toroid and placed within the circular groove 46 of the follower 14. The toroidal contactor 44 is formed with its outer diameter substantially equal to or slightly greater than the maximum inner diameter of the base member 10. In this manner the turns of the coil forming the toroidal contactor 44 are forced over slightly, which may be termed "fall-over," when they are inserted into the base member 10. The resulting pressure on the film caused by the flexure or fall-over of these turns of the toroidal contactor 44 overcomes the rotational force of the lead screw adjustment. Hence, rotation of the lead screw 12, by rotation of the slotted adjustment head 36, advanced the toroidal contactor 44 and follower 14 laterally along the length or axis of the resistance element 26.

A spring 70 and a pair of washers 72 placed on either side of the spring 70 are placed on both ends of the lead screw 12 to provide a clutch action. The washers may be gold-plated brass and the spring beryllium copper. The spring is placed into compression by the inner washers 72 which are located upon shoulders 74 formed at either end of the lead screw 12. These spring and washer combinations act as free running clutches for the follower 14. The lead screw 12 is not threaded at either end to permit the clutch action and the ends (beyond the shoulders 74) are of reduced diameter so that the follower 14 may disengage from the threads as it reaches either end of the film 26. As the follower 14 disengages, it compresses either of the springs 70 such that upon reversal of rotation of the adjustment head 36, the compressed spring 70 forces reengagement of the follower 14 with the threads of the lead screw 12. The clutch action prevents damage to the unit through excessive rotation of the adjustment head 36.

This particular configuration has many advantages. First of all, it provides a multi-point contactor in which a separate contact exists at each turn of the toroidal contactor 44. These several points of contact with the film 26 substantially reduces field effects. The multiplicity of contactors improves reliability in that if one or more turns of the toroid 44 become coated or otherwise develop a higher resistance their effect is small. Additionally, the multiplicity of contactors reduces noise and contact resistance.

The offset positioning of the groove 46 and hence the toroidal contactor 44 in the follower 14 aids in maintaining a positive contact between the film and the toroid contact and in maintaining a positive contact between the follower 14 and the lead screw 12. The fall-over of the toroidal turns provides a light but flexible contact with the film that conforms to any unevenness of the film surface or diameter of the base member 10. The need for additional guides to prevent rotation of the contactor 44 is eliminated by the pressure contact provided by the toroid. The pressure of the toroidal contactor 44 on the film 26 is normal to the film surface and hence the contactor is not directionally sensitive. By the continuous

movement of the toroidal contactor over the film, a very high degree of resolution is obtained.

Having now described my invention in detail, in accordance with the patent statutes, various changes and modifications will suggest themselves to those skilled in this art, and it is intended to cover all such changes and modifications as fall within the true spirit and scope of the invention.

I claim:

1. An adjustable resistor comprising:
an electrically non-conductive tubular base member;
an electrically resistive element on at least a portion of the inside wall of the tubular base member;
a slider adapted to move through the interior of the tubular base member in a direction substantially parallel to the axis thereof;
and an electrically conductive toroidal coil mounted on the slider for providing a multi-point electrical contact between the slider and the resistive element, the coil being mounted so that the plane of the toroid defined by such coil is at an angle effectively different from 90° with respect to the axis of the tubular base member. 10
2. An adjustable resistor comprising:
an electrically non-conductive tubular base member;
an electrically resistive element on at least a portion of the inside wall of the tubular base member;
a slider adapted to move through the interior of the tubular base member in a direction substantially parallel to the axis thereof;
and an electrically conductive toroidal coil mounted on the slider for providing a multi-point electrical contact between the slider and the resistive element, the coil being mounted so that the plane of the toroid defined by such coil is at an angle at least 1° different from 90° with respect to the axis of the tubular base member. 20
3. An adjustable resistor comprising:
an electrically non-conductive tubular base member;
an electrically resistive element on at least a portion of the inside wall of the tubular base member;
a slider adapted to move through the interior of the tubular base member in a direction substantially parallel to the axis thereof;
and an electrically conductive toroidal coil mounted on the slider for providing a multi-point electrical contact between the slider and the resistive element, the coil being mounted so that the plane of the toroid defined by such coil forms an acute angle with the axis of the tubular base member. 30
4. An adjustable resistor comprising:
an electrically non-conductive tubular base member;
a thin electrically resistive film on at least a portion of the inside wall of the tubular base member;
a slider adapted to move through the interior of the tubular base member in a direction substantially parallel to the axis thereof;
and an electrically conductive toroidal coil mounted on the slider for providing a multi-point electrical contact between the slider and the resistive film, the coil being mounted so that the plane of the toroid defined by such coil is at an angle effectively different from 90° with respect to the axis of the tubular base member. 40
5. An adjustable resistor comprising:
an electrically non-conductive tubular base member;
an electrically resistive element on at least a portion of the inside wall of the tubular base member;
a slider adapted to move through the interior of the tubular base member in a direction substantially parallel to the axis thereof;
and an electrically conductive toroidal coil mounted on the slider for providing a multi-point electrical contact between the slider and the resistive element, the outside diameter of the toroid defined by such coil 50

being greater than the inner diameter of the tubular base member and the coil being mounted so that the plane of the toroid is at an angle effectively different from 90° with respect to the axis of the tubular base member.

6. An adjustable resistor comprising:
an electrically non-conductive tubular base member;
an electrically resistive element on at least a portion of the inside wall of the tubular base member;
a cylindrical slider adapted to move through the interior of the tubular base member in a direction substantially parallel to the axis thereof, the periphery of the slider having a groove therein which encircles the axis of the slider, this groove being in a plane which is at an angle effectively different from 90° with respect to the axis of the slider;
and an electrically conductive toroidal coil mounted in the groove on the slider for providing a multi-point electrical contact between the slider and the resistive element. 10
7. An adjustable resistor comprising:
an electrically non-conductive tubular base member;
an electrically resistive element on at least a portion of the inside wall of the tubular base member;
a threaded lead screw rotatably mounted coaxially within the tubular base member;
a cylindrical slider threaded on the lead screw;
and an electrically conductive toroidal coil mounted on the periphery of the slider for providing a multi-point electrical contact between the slider and the resistive element, the coil being mounted so that the plane of the toroid defined by such coil is at an angle effectively different from 90° with respect to the axis of the tubular base member. 20
8. An adjustable resistor comprising:
an electrically non-conductive tubular base member;
an electrically resistive element on at least a portion of the inside wall of the tubular base member;
a threaded lead screw rotatably mounted coaxially within that tubular base member;
a cylindrical slider threaded on the lead screw;
and an electrically conductive toroidal coil mounted on the periphery of the slider for providing a multi-point electrical contact between the slider and the resistive element, the coil being mounted so that the plane of the toroid defined by such coil is at an angle at least 1° different from 90° with respect to the axis of the tubular base member. 30
9. An adjustable resistor comprising:
an electrically non-conductive tubular base member;
an electrically resistive element on at least a portion of the inside wall of the tubular base member;
a threaded lead screw rotatably mounted coaxially within the tubular base member;
a cylindrical slider threaded on the lead screw;
and an electrically conductive toroidal coil mounted on the periphery of the slider for providing a multi-point electrical contact between the slider and the resistive element, the coil being mounted so that the plane of the toroid defined by such coil forms an acute angle with the axis of the tubular base member. 40
10. An adjustable resistor comprising:
an electrically non-conductive tubular base member;
a thin electrically resistive film on at least a portion of the inside wall of the tubular base member;
a threaded lead screw rotatably mounted coaxially within the tubular base member;
a cylindrical slider threaded on the lead screw;
and an electrically conductive toroidal coil mounted on the periphery of the slider for providing a multi-point electrical contact between the slider and the resistive film, the coil being mounted so that the plane of the toroid defined by such coil is at an angle effectively different from 90° with respect to the axis of the tubular base member. 50

11. An adjustable resistor comprising:
 an electrically non-conductive tubular base member;
 an electrically resistive element on at least a portion
 of the inside wall of the tubular base member;
 a threaded lead screw rotatably mounted coaxially
 within the tubular base member; 5
 a cylindrical slider threaded on the lead screw;
 and an electrically conductive toroidal coil mounted
 on the periphery of the slider for providing a multi-
 point electrical contact between the slider and the
 resistive element, the coil being mounted so that the
 plane of the toroid defined by such coil is at an angle
 effectively different from 90° with respect to the
 axis of the tubular base member, the outside diam-
 10 eter of the toroid being greater than the inside diam-
 eter of the tubular base member and such that the
 turns of the coil are caused to flex and exert a
 pressure on the resistive element whereby the friction-
 15 al force of the coil prevents rotation of the
 slider during rotation of the lead screw.
 12. An adjustable resistor comprising:
 an electrically non-conductive tubular base member;
 an electrically resistive element on at least a portion
 of the inside wall of the tubular base member;
 a threaded lead screw rotatably mounted coaxially 25
 within the tubular base member;
 a cylindrical slider threaded on the lead screw;
 an electrically conductive toroidal coil mounted on
 the periphery of the slider for providing a multi-
 point electrical contact between the slider and the 30
 resistive element, the coil being mounted so that the
 plane of the toroid defined by such coil is at an angle
 effectively different from 90° with respect to the
 axis of the tubular base member;
 and means for connecting at least one end of the resis-
 35 tive element and the slider into an electrical circuit.
 13. An adjustable resistor comprising:
 an electrically non-conductive tubular base member;
 an electrically resistive element on at least a portion
 of the inside wall of the tubular base member; 40
 a threaded lead screw rotatably mounted coaxially
 within the tubular base member;
 a cylindrical slider threaded on the lead screw, the per-
 45 iphery of the slider having a groove therein which
 encircles the axis of the slider, this groove being in
 a plane which is at an angle effectively different
 from 90° with respect to the axis of the slider;
 and an electrically conductive toroidal coil mounted
 50 in the groove on the periphery of the slider for
 providing a multi-point electrical contact between the
 slider and the resistive element.
 14. An adjustable resistor comprising:
 an electrically non-conductive tubular base member;
 an electrically resistive element on at least a portion
 of the inside wall of the tubular base member; 55

- a threaded lead screw rotatably mounted coaxially
 within the tubular base member;
 a cylindrical slider threaded on the lead screw;
 an electrically conductive toroidal coil mounted on
 the periphery of the slider for providing a multi-
 point electrical contact between the slider and the
 resistive element, the coil being mounted so that the
 plane of the toroid defined by such coil is at an angle
 effectively different from 90° with respect to the
 axis of the tubular base member;
 at least one end of the lead screw being unthreaded
 for enabling disengagement of the slider from the
 threads of the lead screw adjacent a corresponding
 end of the resistive element;
 and spring means including a spring member coaxially
 positioned over the unthreaded end of the lead screw
 so that the slider compresses the spring member as
 it leaves the threaded portion of the lead screw,
 such compression enabling reengagement of the
 slider on the threads of the lead screw upon a rever-
 sal of its rotational direction.
 15. An adjustable resistor comprising:
 a tubular resistive element;
 an electrically conductive toroidal coil adapted to con-
 tact the surface of the resistive element;
 and means for moving the toroidal coil axially along
 the resistive element while maintaining the plane of
 the toroid defined by such coil at an acute angle
 with respect to the axis of the resistive element.
 16. An adjustable resistor comprising:
 a tubular resistive element;
 an electrically conductive toroidal coil adapted to con-
 tact the interior surface of the resistive element;
 and means for moving the toroidal coil axially through
 the tubular resistive element while maintaining the
 plane of the toroid defined by such coil at an acute
 angle with respect to the axis of the resistive element;
 the outside diameter of the toroid defined by such coil
 being greater than the inside diameter of the tubular
 resistive element and such that the turns of the coil
 are caused to flex and exert a pressure on the resis-
 tive element.
